COMBINED MAILING CASE AND REFRIGERATED CONTAINER FOR FROZEN BIOLOGICAL SPECIMENS

Raymond S. Michel, Portland, Oreg., assignor to United Medical Laboratories, Inc., Portland, Oreg., a corporation of Oregon

Filed June 12, 1967, Ser. No. 7,466

Term of patent 14 years

(Cl. D83—1)

FIG. 1 is a bottom interior plan view of a combined mailing case and refrigerated container for frozen biological specimens;

FIG. 2 is a top interior plan view thereof;

FIG. 3 is an end elevation view taken at a reduced scale and shown partly in section along line 3—3 of FIG. 1 with refrigerated holder removed for ease of illustration; and

FIGS. 4 and 5 are exterior views on a reduced scale of the bottom and top pieces, shown respectively in FIGS. 1 and 2, when combined as a mailing case as shown in FIG. 3.

I claim:

The ornamental design for a combined mailing case and refrigerated container for frozen biological specimens, as shown and described.
